R. J. Hart

Attorney,

UNITED STATES PATENT OFFICE

JULIUS KAHN, OF YOUNGSTOWN, OHIO, ASSIGNOR TO TRUSCON STEEL COMPANY, OF YOUNGSTOWN, OHIO, A CORPORATION OF MICHIGAN

WINDOW STRUCTURE

Application filed February 4, 1930. Serial No. 425,861.

In metal window structures of the type having sliding sash, the problem of preventing infiltration of air is one of considerable moment. The most serious place of leakage 5 occurs through the vertical guide slots of the window-frame and particularly the lower portions of the slots in which the guide swings or flanges of the upper sash operate. These slots are normally open and communicate with the interior of the hollow frame.

The primary object of the present invention is to provide simple and effective means for closing these slots to the extent of cutting 15 off communication between the exterior and the interior of the frame, while allowing the sash guides to move freely.

A further object is to provide means that is readily applicable to the frame, and in 20 case of wear or injury, the closure can be readily removed and replaced.

In the accompanying drawings:

Figure 1 is a view in elevation of the exterior of a window structure of the above 25 type, showing the novel closure in place and one side of the frame being illustrated in section.

Figure 2 is a sectional view on the line 2—2 of Figure 1.

30 Figure 3 is a cross sectional view on an enlarged scale and on the line 3—3 of Figure 1.

Figure 4 is a detail perspective view of a portion of one of the closures.

35 In the embodiment disclosed, a hollow metal window-frame is employed. This includes vertical side members 5, having outer walls 6 and inner walls, the latter including a section 7, a removable section 8, and an inner section 9. The section 8, as clearly 40 shown in Figure 3, terminates short of the sections 7 and 9, thereby producing longitudinal guide slots 10 and 11. The slots 10 are for the inner sash, designated generally 45 by the reference numeral 12. The slots 11 are for the outer sash, designated 13. The inner sash 12 is provided with outstanding 50 guide flanges or wings 14 that operate in the slots 10. The outer sash is provided with

corresponding guide wings or flanges 15 that operate in the slots 11.

Now, it will be evident that with the ordinary structure, when the sash 13 is in its uppermost or closed position, the portions 55 of the slots 11 beneath it afford communication between the outside atmosphere and the interior of the side members 5 of the window-frame. The present invention while addressed particularly to the closing off of such 60 communication for these portions of the slots, is obviously not limited to those particular portions, but the invention may be employed in any or all portions of the said slots.

65 In the present embodiment closure members are employed, each of which preferably comprises a spring bronze sheet or strip bent into trough-form and substantially U or V-shaped in cross section. That is to say, each strip consists of a relatively narrow rear wall 16 with divergent side walls 17. These side walls terminate at their free margins in outwarded flanges 18 and the walls adjacent to the flanges are furthermore longitudinally beaded as shown at 19, so that said beads with 70 the flanges define channels 20 in the outer sides of the said side walls 17. The strips or members are long enough, as shown in Figures 1 and 2 to extend the full length of the portions of the open slots beneath the outer 75 or upper sash 13 and slightly overlap the guide wings or flanges 15. The rear walls 16 are sufficiently narrow to pass through the slots 11 and because of the divergent relation 80 of the walls 17, said walls will be forced toward each other until the opposite edges of the sections 7 and 8 of the inner wall, which edges constitute the side walls of the slots 11, will engage in the channels 20. The walls 17 of the closure members are wide enough 85 so that as clearly shown in Figure 3, the member will surround the portion of the guide flange that projects through the slot and said guide flange can move freely up and down in the channel of the member. If desired and in order to insure these closure members against displacement the flanges 18, which lie against the inner faces of the frame wall sections 7 and 8, may be provided 90 with openings 21 to receive suitable fasteners. 95 100

It will be evident that these members when in place in the normally exposed portions of the guide slots, close the same against the entrance of air into the interior of the window frame. They are readily insertible and removable and do not require material modification of the window frame structure.

From the foregoing, it is thought that the construction, operation and many advantages of the herein described invention will be apparent to those skilled in the art without further description and it will be understood that various changes in the size, shape, proportion and minor details of construction may be resorted to without departing from the spirit or sacrificing any of the advantages of the invention.

What I claim is:—

1. In combination with a hollow window frame having a wall provided with a guide slot and a sash having a guide slidably engaged in the slot, of a trough-shaped weather shield forming a closed channel behind the slot and embracing the portion of the guide engaged therein, and having its opposite sides engaged in the slot on opposite sides of the guide therein.

2. In combination with a window frame including an inner side wall having a guide slot, and a sash having a guide flange slidable in the slot, of a channeled member insertible through the slot from the exposed side of the wall and extending around the rear portion of the guide flange engaged in the slot, the free margins of the sides of the members being engaged in the slot on opposite sides of the guide flange.

3. In combination with a window frame including an inner side wall having a guide slot, and a sash having a guide flange slidably in the slot, of a channeled member insertible through the slot from the exposed side of the wall and having side walls engaged with the walls of the slot on opposite sides of the guide flange, said channeled member extending around the rear portion of the guide flange engaged in the slot.

4. In combination with a window frame including an inner side wall having a guide slot, and a sash having a guide flange slidably in the slot, of a channeled member having its closed side insertible through the slot from the exposed side of the wall and having side walls provided with means that interfit with the walls of the slot to position the channeled member, said member extending around the rear portion of the guide flange engaged in the slot.

5. In combination with a window frame including an inner side wall having a guide slot, and a sash having a guide flange slidably in the slot, of a channeled member insertible through the slot from the exposed side of the wall and having side walls provided with outwardly ribbed portions that

embrace the walls of the slot on opposite sides of the guide flange and position the channeled member, said member extending around the rear portion of the guide flange engaged in the slot.

6. In combination with a hollow metal window frame having inner side walls provided with longitudinal guide slots, and a sash movable in the window frame and having guide flanges extending into and slidable in said slots, of channeled slot closures extending behind and across the slots around the guide flanges, and each having side walls on opposite sides of the flanges engaged in the slot of the side wall.

7. In combination with a hollow metal window frame having inner side walls provided with longitudinal guide slots, and a sash movable in the window frame and having guide flanges extending into and slidable in said slots, of channeled slot closures fitted longitudinally into the slots and extending into the window frame, said closures surrounding the portions of the guide flanges that extend through the slots, and having portions engaged with the walls of the slots on opposite sides of the guide flanges therein.

8. A slot closure for metal window frames comprising an elongated channeled strip of a width to enter and be seated in the guide slot of a metal window frame and surround the guide flange of a sash engaged in said slot, said strip having a rear wall and side walls, the latter having means for embracing the edges of the window frame wall that are on opposite sides of the slot.

9. A slot closure for metal window frames comprising an elongated channeled strip of a width to enter and be seated in the guide slot of a metal window frame and surround the guide flange of a sash engaged in said slot, said strip having a rear wall and side walls, the latter having channels in the outer sides to receive the edges of the window frame wall that are on opposite sides of the slot, and said strip being resilient to cause the walls to spread apart.

In testimony whereof, I affix my signature.
JULIUS KAHN.
